UNITED STATES PATENT OFFICE.

MICHAEL LOCK, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

WIRELESS TELEGRAPHY AND TELEPHONY.

Application filed December 5, 1922, Serial No. 604,999, and in Germany December 20, 1921.

In wireless communication and particularly in wireless telephony in order to make possible simultaneous transmission and reception without switching operations, it has 5 heretofore been proposed to select waves of two different frequencies for a connection. For example, it has been proposed to operate the sender of one station at a carrier frequency a to which the receiver of the 10 other station is tuned, and to operate the sender of the latter station at a different carrier frequency b to which the receiver of the first-mentioned station is tuned. In this manner transmission and reception may be 15 effected at two independent carrier frequencies whereby communication in opposite directions is possible.

In view of the fact that for a certain number of conversations only a limited number 20 of wave lengths are at disposal, the use of two wave lengths for a conversation constitutes always a poor utilization of the given number of wave lengths. It is impossible to have the two wave lengths necessary for a 25 conversation very near each other because in that case the receiver will be considerably influenced by its associated sender whereby the sensitiveness of the receiver will be reduced.

30 An object of the invention to be herein-after set forth is to make possible conversation in opposite directions by means of a single wave length. To this end, a tube arrangement is used which serves for both 35 sending and receiving and which, through the agency of special means, is alternately operated exclusively as a sender or as a receiver. This alternation in the operation of the tube arrangement as a sender and as a 40 receiver occurs so quickly that it is not audible and will not alter the character of speech in telephony.

In the drawing—

45 Fig. 1 is a diagrammatic representation of a circuit arrangement embodying the invention, and

Fig. 2 is a graphic illustration of the changes in potential impressed upon the second grid of the main vacuum tube.

50 In the illustrated arrangement, 1 is an antenna circuit, and 2 is a coil which together with condenser 3 constitutes an oscillating circuit. In the well known manner this circuit is energized by undamped oscil-

lations generated by the tube 4. The conductor leading to the controlling grid 5 includes a telephone transmitter 6 and the anode circuit includes a receiver 7. The tube may, for instance, have two grids and its second space charging grid 8 may be 60 connected with an ohmic resistance 9 provided in the anode circuit of a cathode tube 10. The grid 11 of cathode tube 10 has an alternating potential impressed on it by the small auxiliary oscillator 12. The frequency 65 of this potential will determine the timing of the alternation in the operation of the tube 4 as a sending and as a receiving tube. This is attained by the production in the well known manner shown in Fig. 2, in 70 which w denotes potential and t time, of a potential at the ohmic resistance and therefore at the space charging grid 8 of the tube 4. This potential on the space charging grid 8 controls the anode current in the tube 4, 75 i. e. it decreases the latter for a definite period of time and then permits it to rise again. When the anode current is small, the tube 4 will cease to oscillate and operates as a receiver. When this current is large, the tube operates as a sender. This makes possible the alternate operation of the arrangement as a sender and as a receiver.

It is not necessary that a circuit arrangement of the particular type shown in Fig. 1 85 be used. Any vacuum tube or amplifying arrangement may be employed, which is the equivalent of the last-mentioned arrangement. So long as the tube circuit effects the generation of the carrier frequency, the character of the arrangement is immaterial from 90 the standpoint of the invention.

Having described my invention I declare that what I claim is

1. In a signalling system using radio frequency, a thermionic tube having at least three electrodes, means for causing the tube to produce oscillations to enable it to be operated as an oscillator, and for intermittently decreasing the current in the anode 100 circuit of the tube to cause it to cease to function as an oscillator and to function as a detector, said means operating at an inaudible frequency.

2. In a signalling system using radio frequency, a thermionic tube having a cathode, anode, and grid, the anode circuit and grid circuit being regeneratively coupled, a

- fourth electrode in said tube, means for impressing a changing potential on said fourth electrode so as to alternately cause said tube to function as an oscillator and as a detector, the frequency of the alternations being inaudible. 40
3. In a signalling system using radio frequency, a thermionic tube having at least three electrodes, the grid and plate circuits being regeneratively coupled, telephone receiving means in said plate circuit, telephone transmitting means in said grid circuit, and means for intermittently decreasing the plate current of the tube so as to prevent functioning of the tube as transmitter and to cause it to function as a detector, said last mentioned means operating at an inaudible frequency. 45
4. In a signalling system using radio frequency, a vacuum tube, means whereby the vacuum tube may function as a generator of oscillations or as a detector, and additional means for alternately and automatically causing said vacuum tube to function as a generator and as a detector. 50
5. In a signalling system using radio frequency, a vacuum tube, means whereby the vacuum tube may function as a generator of oscillations or as a detector of oscillations, and additional means for alternately causing said vacuum tube to function as a generator and as a detector, the frequency of the alternations being inaudible. 55
6. In a signalling system using radio frequency, a thermionic tube, means whereby said tube may function as an oscillator for sending or as a detector for receiving, and additional means for alternately causing said tube to function as an oscillator and as a detector. 60
- a detector, the frequency of the alternations being above audibility. 65
7. In a signalling system using radio frequency, a thermionic tube having a cathode, anode and grid, means for alternately causing the tube to produce oscillations for sending and causing the tube not to oscillate for receiving, said means operating at an inaudible frequency, and comprising a fourth electrode in the tube, a thermionic tube amplifier connected to the fourth electrode, and a master oscillator feeding said amplifier. 70
8. In a signalling system using radio frequency, a thermionic tube having a cathode, anode and grid, means for causing said tube to produce oscillations, and means for intermittently decreasing the anode current of the tube to cause it to cease to function as an oscillator and simultaneously to cause it to function as a detector, said means operating at inaudible frequency and comprising a thermionic tube amplifier having an ohmic resistance in its anode circuit, a fourth electrode in the first-mentioned tube connected to the anode circuit of the amplifier between said resistance and the anode of the amplifier, and a master oscillator coupled to the grid-filament circuit of the amplifier for causing it to impress changing potentials on said fourth electrode. 75
9. In a signalling system using radio frequency, a thermionic tube having a cathode, anode, and grid, the anode circuit and grid circuit being regeneratively coupled, a fourth electrode in said tube, means for impressing a changing potential on said fourth electrode so as to alternately cause said tube to function as an oscillator and as a detector. 80
